UNITED STATES PATENT OFFICE

108,747

DESIGN FOR A KNIFE HOLDER

Horner H. Hopkins, Des Moines, Iowa

Application November 12, 1937, Serial No. 72,821

Term of patent 14 years

To all whom it may concern:

Be it known that I, Horner H. Hopkins, a citizen of the United States and resident of Des Moines, Polk County, Iowa, have invented a new, original, and ornamental Design for a Knife Holder, of which the following is a specification, reference being had to the accompanying drawing, forming a part thereof.

Fig. 1 is a perspective view of the knife holder, showing my design; and

Fig. 2 is a top plan view thereof.

I claim:

The ornamental design for a knife holder, substantially as shown.

HORNER H. HOPKINS.
